[57] **ABSTRACT**

A filing and retrieval system whereby alphabetic name and titles are interpreted by numeric code. This can be done by following a set of rules manually. The encoding of words including names is characterized in the dividing of the word into phonic sounds, irrespective of the actual spelling of the word, and the assignment of a numeric code to each phonic sound excepting the first sound, followed by the filing of items bearing the numeric code in serial order, without regard to the spelling of the word, thereby permitting the retrieval of a filed item even if the exact spelling is not known.

3 Claims, No Drawings

CODED FILING AND RETRIEVAL SYSTEM

This application is a continuation in part of my corresponding application, Ser. No. 65,310, filed Aug. 19, 1970 now abandoned.

The problems of alphabetic filing have always been great. The training of clerks for skillful alphabetic filing is long and expensive, and the file clerk, for all her special skills, has been regarded as low echelon, and accordingly she has been low paid in comparison with stenographers, secretaries, and other female positions. Comparatively few males are engaged in filing work. The problem of retaining skilled file clerks grows steadily because of their attraction to other better paid positions which often are less exacting and demanding for patience, tedium, and concentration. Name filing and retrieval is complicated with any alphabetic system because each letter of the name or names must be sequentially filed in strict alphabetic arrangement for each character. The least error in spelling or misreading can result in misfiling, which may make retrieval almost impossible.

The disclosed system translates to numbers the alphabetic names. Because the system is a short-cut to filing, certain parts of names are treated differently from ordinary alphabetic filing.

It is therefore among the principal objects of the present invention to provide an improved filing and retrieval system, which permits greater speed in both filing and retrieval than has heretofore been the case with alphabetic systems.

Another object of the invention lies in the provision of an improved filing and retrieval system capable of greater accuracy than has been the case with alphabetic systems.

A further object of the invention lies in the provision of an improved filing and retrieval system of the class described permitting a positive system of audit.

These objects, as well as other incidental ends and advantages, will more fully appear in the progress of the following disclosure, and be pointed out in the appended claims.

BRIEF DESCRIPTION OF THE PRIOR ART

The U.S. Pat. to Schmidt, No. 1,305,939, discloses an alphanumeric system using the first letter of the word, and the assignment of one of 10 digits to cover any of a group of adjacent characters. It requires the use of a chart for encoding, and each letter is assigned a digit which in part depends upon the identification of the previous letter in a word. The Wagner U.S. Pat., No. 1,685,206, teaches an equally complex system.

BRIEF DESCRIPTION OF THE INVENTION

Briefly stated, in the present system, the alphabet is classed into 10 basic sounds. Immediately, instead of 26 possible sequences for alphabetic characters, there are only 10. This reduces substantially the number of possible filing sequences for each name. The 10 sonic classifications involve the consonants only. The vowels and "h" and "y" are ignored because they are practically noncontributory to the sound of a name or syllable, the exceptions being the aspirate "h" as in "Hansen" or the sound of "y" as in "Young". Although "h" preceded by "c" (making "ch") results in the "chay" sound, for purposes of coding, the "c" is sufficient, and in most names the "h" is not sounded, as in "Dwight,"

"Light," and "Wright." The "y" is most often used as a vowel as in "Blayder," "Blyth," "Bay," and "Holly."

In teaching the sounds of English letters, the vowels are expressed "a" as in "at," "e" as "eh," "i" as "ih," "o" as "oh," and "u" as "oo." A consonant is expressed as if a vowel follows it. For example, the "l" is pronounced "el" but phonetically it is pronounced "leh;" "m" is pronounced "em," but phonetically "meh;" "b" is pronounced "bee" but phonetically "beh;" "g" is pronounced "jee," but phonetically "geh." In the Pitman shorthand system, for uniformity all sounds are expressed with the long "A," "b" pronounced "bay," "p" pronounced "pay," "l" pronounced "lay," etc. For uniformity, I have done the same with the disclosed system.

In order to sound the letter "b," we say in English "Bee," in French "Bay," in German "Beh." Thus the name "Bendix," omitting the vowels to spell "Bndx" would sound similar whether pronounced "Bayndax," "Behndex," "Bandox," or "Beendex."

In filing, for example, the name "Bendix" strictly alphabetically among a large series of names, each of the six letters has 26 possible sequences. In the instant filing, the name "Bndx" has only 10 possible sequences for four translated characters. Now if "Bndx" is translated to 18-30 to read "eighteen-thirty," it is easily sorted and interfiled with other names similarly coded in paired-off numbers. If the word were "Pentix" rather than "Bendix," it would be assigned the same code number, and would be filed in the same place.

Because numbers are easier to read, remember, sort, and file than a series of alphabetic letters, the instant system reduces mis-files and increases the speed of filing.

Although index guides will assist in finding one's place in an alphabetic file, careful discrimination still has to be made among names filed behind any one guide. In fact, careful discrimination must be made to find the correct guide.

DETAILED DESCRIPTION OF THE INVENTION

In accordance with the invention, the system deals with 10 digits, zero through nine, which are assigned to alphabetic characters as follows:

Code No.	Letter(s)	Sounds Like
1	b, p	bay, pay
2	c, g, k, q	cay, kay, gay, quay
3	d, t	day, tay
4	f, v, w	fay, vay, way
5	j	jay
6	l	lay
7	m	may
8	n	nay
9	r	ray
0	s, x, z	say, xay, zay

It will be observed that letters are grouped together where they are similarly vocalized or pronounced. Thus, "b" and "p" are both plosive sounds, and thus are assigned the same code number "1." In a similar fashion, "c," "g," "k" and "q" which are formed at the rear of the palate contacting the tongue are assigned code number "2." "d" and "t" are front palate sounds, and both are assigned code number "3." In a similar fashion, labial, nasal, fricative, sibilant and other sounds are grouped together to be assigned one code number for all.

Alphabetic letters are coded for basic phonic sounds only. Because the vowels "a," "e," "i," "o" and "u" and the letters "h" and "y" are not basic phonic sounds, they are ignored.

Because a single or double consonant forms the same basic phonic sound, double consonants are coded as a single phonic. Likewise, different consonants which produce the same phonic sound, if they are in juxtaposition, are coded as a single phonic.

Example: Farrington	Code: F 9 82	double phonic "ray" in juxtaposition treated as one
Becker	Code: B 2 9	similar phonic "kay" following the like coded phonic "kay" treated as one.

By breaking down language (or names) into 10 basic sounds, the instant system assigns a distinct and unique numeral to each root sound and eliminates the codification of non-contributory sounds. However, of corollary importance is the unique treatment of names, not as separate surname, given, and middle names, but as whole names. Without this corollary technique, the numerals contained in a given code could not be limited to six (not that many names are coded in less than six.)

For example, "Kaye, Danny" a compound name of nine letters, translates to "38." Or to use an example cited by Wagner, "Smith, George Stewart," a compound name of 18 letters, translates in the disclosed system to "73-29-20." The abbreviatory process is of great significance in filing and cannot be accomplished in any system of coding each letter.

Personal names are coded surname first, followed by first name and initials. The code treats surname, first name and initials as though they are one name, the digits simply being set off in pairs.

Example: Anderson, Jack P.	Code: A83 9 5 2 1	expressed as A83 95 21

The surname retains its first alpha character followed by three numeric codes. The given (first) name gets three numeric codes also. If not all six digits have been used, any initials are picked up by the code.

Example: Abt, Oswald C.	Code: A13 04 63	expressed as A13 04 63
Example: Abt, Joseph L.	Code: A13 5 0 1 6	expressed as A13 50 16
Example: Abbott, Worthington	Code: A1 3 4 93	expressed as A13 49 3

The instant system does not involve alphabetic filing at all. The numeric equivalents of the phonetic sounds are filed according to the primary pair of numerals. Thus, in the translated names

Ball, Roy J.	expressed as B 69 5
B 6 9 5	
James, Harry S.	expressed as J 70 90
J 7 0 9 0	
Kaye, Danny	expressed as K 38
K 3 8	

These names would be filed according to the primary pair of numerals, respectively "69," "70," and "38." The alphabetic character is not the key to the instant system nor is it employed in the filing process. The

unique combination of the root phonetics translate into a unique combination of numerals, and filing is done only according to the number, not by letter.

In very large alphabetic files involving identical personal names, the coder may suffix the trans-sonic code with up to three numerals of the house number, or in the absence of a house number, the Post Office Box number, or the trans-sonic code for the street, road or highway.

10

Example: Smith, John	Code: S 73 58 (139)
Becker	Example: Smith, John
Code: B 2 9	P. O. Box 212
	Poughkeepsie, N.Y.

20

While the foregoing deals with personal names, the disclosed system applies also to impersonal names. For impersonal (firm) names, the first name of the title retains its first alpha character (subject to the modifying rules herein) followed by three numeric codes.

If the first word of a title requires less than three numeric codes, we continue to code the following name to a maximum of three numeric codes. If this does not complete the code (alpha plus six numeric), we continue to code successive words to complete the code. If there are no successive words, we code the succeeding second word or the first word to the limit of the six numeric codes.

35

Example: Ace Comb Corp.	Code: A2 2 71
Example: Arch Accounting & Statistical Corp.	Code: A92 2 83 0
Example: International Telephone & Telegraph Co.	Code: 18 3 6 1 3 6
Example: Ackerson Bus Co.	A2 90 8 1 0
Example: Expositions, Inc.	Code: E01 0 3 80

The following words are ignored: "a," "and," "&," "by," "for," "from," "into," "of," "for," "onto," "to," "with," "company," "Co.," "Incorporated," "Inc.," "Limited," "Ltd."

Unless they are the first word of a title, the following words are ignored: "Associate(s)," "Associated," "Association," "Bank," "Board," "Bureau," "Chamber," "Central," "Church," "Committee," "Commission(ers)," "Grand," "Great(er)," "Consolidated," "Federation," "Foundation," "Institute," "Organization," "Society," "State(s)," "United," "Street," "Avenue," "Road," "Highway," "Parkway."

If they are the first word of a title, they are coded by retaining the first alpha character followed by one numeric digit for the succeeding letter.

60

Example: Associated Investors	Code: A0 84 03 9
Investors Associates	
	Code: I84 0

Hyphenated and compound names are treated as one word.

Example: Mel-Tec, Stan-ray

The following words are restricted to two numeric codes unless they are the first word of a title, in which case they retain the first alpha letter followed by one numeric code for the succeeding letter: American, America(s), General, International, National.

Similarly coded are the compass points: East(ern), West(ern), North(ern), South(ern).

Titles expressed in numerals are given the alpha letter "N" for "number" followed by up to three digital codes.

Example: 150 Broadway Corp.

Code: N150 19 3

Example: 500 Fifth Avenue Corp.

Code: N500 5

Titles expressed in spelled out numbers are treated as though they were written in numerals and are given the alpha letter "N" for "number" followed by the spelled out number expressed in numerals.

Example: One Twenty Broadway Corp.

Code: N 1 20 19 8

Example: Sixty Eighth Street Theatre

Code: N 60 8 3 39

Compound place names (those representing towns or cities are usually so identified in the address city) are treated as one word unless part of the name is a compass point.

Example: Rocky Mountain Express Co.

Code: R 2 7 8 019

Example: Central Park Laundry

Code: C 8 19 6 83

Example: Port of New York Authority

Code: P 93 8 4 9 3

Example: Palo Alto Plumbing Supply Co.

Code: P 6 63 16 7

Example: East Haddam Supermarket

Code: E 0 3 7 0 1 9

Names prefixed "AAA," "AAAA," "BBB," etc., used to get preferred directory listing, only the first letter retains its alpha character and the succeeding letters are ignored.

Example: AAAA Window Cleaners

Code: A 4 83 26 8

Example: ABC Automotive Parts Co.

Code: A12 3 7 3 4

Numbers are set off in pairs beginning after the first alpha letter.

With a number filing system, the maximum six digits, paired-off, are quickly read, remembered, and interfiled among other numbers.

In a series of numbers paired-off, such as

20 49 05
21 49 05
22 56 66
23 67 48
30 30

the pair to the left is the primary pair, the next pair secondary, and the third pair (if any) tertiary. Interfiling of numbers is fast and accurate, and in a large file, set up with primary guides, the file clerk is looking only for the first pair, say "20." Secondary guides in the file would lead her to, for example "40," and the only "fine-filing" necessary is for the third pair, and that only

in a very large file sequence because one file for each of four digits is already 10,000 files.

It may thus be seen that my system offers many advantages over conventional alphabetic systems. With straight line alphabetic filing, the only augmentative device which is available is an alphabetic guide system. An alphabetic guide system can range from the simplest one of 24 guides signals A through W plus one for X, Y, Z, to a system of guides ranging from 40 divisions and up to a thousand or more divisions. But even in a large guide system where the letter B is guided for Ba, Bab, Bac, Bad, Baf, Bag, Bah, Bai, etc., not only does the preliminary fine-sorting of a large number of documents or folders involve a painstaking and laborious process of multiple sorts, but extra time and care to interfile the documents within the exact guide position is necessary.

The conversion of alphabetic filing to a numeric system allows the introduction of several new augmentative devices and techniques to simplify and speed up the filing system.

Firstly, the system of paired-off numbers, makes reading easier, quick, and more accurate. With a six digit number set out in three pairs, a large volume of papers can be quickly sorted down into the 100 possible divisions of the first pair. At the file, the papers are quickly interfiled for the second pair of numbers (whether into "tens" or "ones," depending on the extensiveness of the file system).

Secondly, the use of color coding (a color representing each number "zero" through "nine") becomes possible. The colored sticker or other designation affixed to the exposed edge of a file folder immediately exposes misfiling. If for example, a red sticker stands for "7" and a blue for "9," all files with primary digits "79" would be colored alike. A wrong number would be exposed immediately. In large file sequences, the secondary pair of numbers can be similarly identified by color.

Thirdly, numeric filing makes possible the use of electro-mechanical sensing and retrieval systems which, because of the complexity of alphabetic sensing, are limited to number systems.

Fourthly, the filing and retrieval code, once established for an account name, can be affixed to all outgoing correspondence, invoices, and other documents either as a permanent reference number or as part of any other identifying number, such as an account number. Placed on outgoing invoices and order confirmations, for instance, in the name and address box, the number would be on the thousands of carbon copies which daily have to be filed by account name in thousands of business firms each day.

Fifthly, the system can be programmed into a small machine which, when the name is typed out, translates and writes out the filing and retrieval code, whether on a label, a title insert strip, or on a document.

Sixthly, a straight alphabetic file system of any considerable size, is almost impossible of audit. A misfiled folder is usually lost until it is accidentally discovered when interfiling something adjacent to the misfiled folder. No system of auditing strict alphabetic files except by meticulous review, one-by-one is possible. The disclosed system, filed by pairs of numbers, greatly reduces the chance of misfiling and furthermore, with

the enabling of color coding, provides a quick means of audit. Because the system translates alphabetic names into a number code according to known fixed rules, any code number can be reconstructed without consulting a reference-number log book or index such as is required for a non-meaningful sequential number system used for licenses, insurance policies, and liability claims.

Where required, the concept and principles of the system can also be expanded to a larger number, if needed, for example, to deal with a multi-million name-file system such as for governmental agencies, credit cards, or travel checks business.

It will be observed that because of the phonic sound relationship of the assigned code, it is possible to retrieve items which have been encoded using the last name of an individual, even where the exact spelling of the name is not determined. Although in all circumstances, the initial letter of the encoded word is included in the code, the items are physically filed on a strictly numerical basis, so that, for example, the name "Kahn," will be readily located, irrespective of whether the retriever assumes the name is spelled "Cahn," "Kahn," etc.

I wish it to be understood that I do not consider the invention limited to the precise details set forth in this specification, for obvious modifications will occur to those skilled in the art to which the invention pertains.

I claim:

1. The method of alpha-numerically encoding an alphabetic filing system of individual items including dividing a word to be encoded into phonic sounds, assigning a digital number to at least one sound following the initial sound in accordance with a preestablished pattern classifying the phonic sounds by the manner in which it is vocally produced, and filing coded items in accordance with the assigned digital numbers, irrespective of the initial letter of the encoded word, and the spelling thereof.

2. The method in accordance with claim 1, in which said pattern translates:

Code No.	Letter(s)
1	b, p
2	c, g, k, q
3	d, t
4	f, v, w
5	j
6	l
7	m
8	n
9	r
0	s, x, z

3. The method in accordance with claim 1, in which each digit is assigned a distinct color, and correspondingly colored stickers are affixed to said items to facilitate auditing of a group of items for misfiling.
